HEEL FOR LADY'S SHOE

Ivo Barbaresi, Florence, Italy, assignor to Salvatore Ferragamo S.p.A., Florence, Italy

Filed Feb. 12, 1969, Ser. No. 15,748

Claims priority, application Italy Oct. 1, 1968

Term of patent 7 years

Int. Cl. D2—04

U.S. Cl. D2—325

FIG. 1

FIG. 2

FIG. 3

FIG. 4

FIG. 1 is a side elevational view of a heel for a lady's shoe, showing my new design;

FIG. 2 is a bottom plan view thereof;

FIG. 3 is a rear elevational view with the heel tilted forward; and

FIG. 4 is a side perspective view taken from below the heel.

I claim:

The ornamental design for a heel for lady's shoe, substantially as shown.
